[57] CLAIM

The ornamental design for a dispensing nozzle for a container, substantially as shown and described.

DESCRIPTION

FIG. 1 is a top plan view of a dispensing nozzle for a container showing my new design;

FIG. 2 is a bottom plan view;

FIG. 3 is an elevational view;

FIG. 4 is an elevational view showing the side opposite that seen in FIG. 3;

FIG. 5 is an elevational view looking from the left in FIG. 3; and

FIG. 6 is an elevational view looking from the right of FIG. 3.
